INVENTOR:—

Ida N. Kelly:—
By Hazard & Miller
ATTY.S.

UNITED STATES PATENT OFFICE.

IDA N. KELLY, OF LONG BEACH, CALIFORNIA.

DESIGN FOR A NIGHT-SHIRT.

59,012.

Specification for Design. Patented Sept. 13, 1921.

Application filed March 24, 1921. Serial No. 455,160. Term of patent 14 years.

To all whom it may concern:

Be it known that I, Ida N. KELLY, a citizen of the United States, residing at Long Beach, in the county of Los Angeles and State of California, have invented a new, original, and ornamental Design for Night-Shirts, of which the following is a specification, reference being had to the accompanying drawing, forming a part thereof.

Fig. 2 is a rear view thereof.

I claim:

The ornamental design for a night shirt as shown.

IDA N. KELLY.
